(57) **CLAIM**

The ornamental design for a broadcast spray nozzle, as shown and described.

DESCRIPTION

FIG. 1 is a front perspective view of a broadcast spray nozzle showing my new design;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a side view thereof;

FIG. 8 is a front perspective view of a nozzle body making up part of the spray nozzle shown in FIG. 1;

FIG. 9 is a rear perspective view of the nozzle body shown in FIG. 8;

FIG. 10 is a top view of the nozzle body shown in FIG. 8;

FIG. 11 is a bottom view of the nozzle body shown in FIG. 8;

FIG. 12 is a front view of the nozzle body shown in FIG. 8;

FIG. 13 is a rear view of the nozzle body shown in FIG. 8;

FIG. 14 is a side view of the nozzle body shown in FIG. 8;

FIG. 15 is a front perspective view of a deflector making up part of the spray nozzle shown in FIG. 1;

FIG. 16 is a rear perspective view of the deflector shown in FIG. 15;

FIG. 17 is a top view of the deflector shown in FIG. 15;

FIG. 18 is a bottom view of the deflector shown in FIG. 15;

FIG. 19 is a front view of the deflector shown in FIG. 15;

FIG. 20 is a rear view of the deflector shown in FIG. 15; and,

FIG. 21 is a side view of the deflector shown in FIG. 15.
